HEAT EXCHANGER

Raymond W. Avery, Kings Norton, Birmingham,
and Kenneth J. Dangerfield, Selly Oak, Bir-
mingham, England, assignors to The Austin
Motor Company Limited, Birmingham, England

Application November 27, 1951, Serial No. 258,324
In Great Britain December 13, 1950

5 Claims. (CL. 219—10)

1

This invention relates to heat exchangers, more particularly for use in connection with turbine plant, for transferring heat from the turbine gases to the compressed inlet air. The type of heat exchanger to which the invention relates is that in which a series or cluster of tubes of small diameter in relation to their length is mounted in end plates, the whole being enclosed by an envelope which is gas tight and is furnished with appropriately positioned inlet and outlet openings. The gas to be cooled may pass through the tubes and the air may pass through the envelope and over or around the tubes, or said gas may pass over or around the tubes and the air may pass through them.

The present invention has for its object to provide a new or improved method of and means for securing the ends of the tubes in their mounting holes in the end plates in a gas tight manner.

The method according to the invention consists broadly in employing resistance welding, commonly known as "spot welding," to make the joint between the metal of the tube end and the surrounding metal of the end plate, such welding being performed by causing a large electric current to flow from an electrode at one outer side of the end plate and through the metal of the tube end and that of the plate to another electrode at the other inner side of the plate, said current being maintained for a sufficient period to ensure fusion of the parts to be joined.

The electrode at the outer side of the end plate preferably will be provided with a conical end for engaging in the tube end.

The end of the tube at the outer side of the plate preferably will be flared or flanged and the conical-ended electrode will be accurately shaped to fit the end of the tube and conform to the flare or flange thereon.

The second electrode at the inner side of the plate preferably will be shaped to straddle the tube, and will be formed with blunt projections for making two local area contacts with the plate on either side of the tube at diametrically opposed points. Said second electrode may be provided with an insert of insulating material between the portion of the electrode which straddles the tube and the tube itself.

The invention will now be further described with reference to the accompanying drawings, in which:

Fig. 1 is a perspective view of a pair of electrodes.

Fig. 2 is a side elevation, partly in section, of a

2

portion of a heat exchanger and the pair of electrodes.

Referring to the drawings, the pair of electrodes comprises an upper electrode 10 provided with a conical end 11, and a second lower electrode 12. The lower electrode 12 is provided with two extension portions 13, which both extend laterally from the main body of the electrode at the edges of one side face thereof, and also extend upwardly as two blunt projections 14 having contact faces 15. Between the two laterally projecting portions 13 is located a U-shaped insert 16 of insulating material. The two electrodes may be used in a normal pedestal type spot-welder.

Referring particularly to Fig. 2 of the drawings, a portion of one end plate of a heat exchanger in process of construction, is shown at 17. Portions of two tubes 18 are shown with their end portions 20 spot welded into the plate 17. A third tube 19 is in position ready for welding and holes for the reception of the end portions of further tubes are shown at 21.

The tube 19 has its end portion 22 located in a through hole in the plate 17, and the very extreme end of the tube has been provided with a flare or flange 23.

The first electrode 10 is at the outer side of the plate and ready to be moved downwardly, as when mounted in a pedestal spot-welding machine, whilst the second electrode is at the inner side of the plate, and by reason of its shape it straddles the tube 19, the contact faces 15 of the blunt projections 14 making two local area contacts with the plate 17 on either side of the tube 19 at diametrically opposed positions, the insulating insert 16 preventing any electrical contact between the tube and the second electrode.

The conical-ended electrode 10 has its end 11 accurately shaped to fit into the end 22 of the tube 19 and conform to the flare or flange 23 thereon when said electrode is lowered into welding contact with the said tube, and the flare or flange 23 prevents the tube 19 being pushed through or further into the hole in the plate 17 by the pressure of the conical electrode, before fusion has taken place.

The welding current in passing from the contact faces of one electrode to the other is constrained to pass through both the tube end and the plate itself, and by providing an accurately shaped electrode with a conical spigot portion to fit in the end of the tubes having a shoulder or side face to conform to the flare or flange thereon, and also by the provision of a second bifur-

cated electrode to straddle the tube on the inner side of the end plate, the making of resistance welded efficient gas tight joints between the tube ends and the end plates can be carried out expeditiously as the assembly is built up tube by tube as illustrated in Fig. 2 of the drawings.

The actual size of the contact areas 15 of the second bifurcated electrode would be varied as found necessary to suit the characteristics of the metal used for the tubes and end plates, and also to suit the relative dimensions of tubes and plates, pitch of tubes, and the like.

Having fully described our invention, what we claim and desire to secure by Letters Patent is:

1. The method of resistance welding a tube to a plate, wherein the tube is receivable within an opening in the plate and the exterior wall of the tube adjacent the end thereof contacts the metal of the plate around said opening, which comprises supporting the plate at one side thereof at spaced apart points spaced from the wall of the tube, moving an electrode into engagement with the end of said tube at the other side of the plate, and passing a welding current from said electrode through the metal 25 of the tube end and the immediately surrounding metal of the plate to said spaced apart points of support, said current being maintained for a sufficient period to insure fusion of the tube and the plate.

2. The method as set forth in claim 1 wherein said electrode is moved into annular engagement with the end of said tube.

3. The method as set forth in claim 1 which

comprises in addition, flaring the end of the tube, and moving the electrode into annular engagement with the flared end of the tube.

4. Mechanism for resistance welding a tube to a plate, wherein the tube is receivable within an opening in the plate and the exterior wall of the tube adjacent the end thereof contacts the metal of the plate around said opening, comprising an electrode having spaced apart portions straddling the tube, said portions engaging the plate at one side thereof, a second electrode positioned at the other side of the plate and movable into engagement with the end of said tube, and means for passing a welding current from the second electrode through the metal of the tube end and the immediately surrounding metal of the plate to said spaced apart portions of the first named electrode.

5. Mechanism as set forth in claim 4 which comprises in addition, an insulating member positioned between the portions of the first named electrode and spaced from the tube.
